ABSTRACT OF THE DISCLOSURE

Novel 21-sulfinyl steroids, having utility as anti-inflammatory agents, are disclosed.

SUMMARY OF THE INVENTION

Novel 21-sulfinyl steroids having the following formula:

(I)

have been found to be anti-inflammatory agents. In Formula I, and throughout the specification the symbols have the following meanings:

R₁ may be lower alkyl, cycloalkyl, aryl, or aralkyl;

R₂ may be hydrogen, lower alkyl or hydroxy;

R₃ may be hydrogen, lower alkyl, methylene, or hydroxy;

Alternatively, R₂ and R₃ may together form a cyclized dioxolo group, i.e.

or a cyclized oxazole group, i.e.

wherein R₄ and R₅ may be the same or different and may be hydrogen, lower alkyl or aryl (however, both cannot be hydrogen), or R₄ and R₅ may together form a cycloalkyl group, and wherein R₆ may be lower alkyl; X₁ may be hydroxy or halogen; X₂ may be hydrogen or halogen; X₃ may be hydrogen, lower alkyl, or halogen. The dotted lines within the ring system indicate the optional presence of a carbon-carbon double bond.

In making the 21-sulfinyl steroids of Formula I, intermediates having the following formulas may be used:

(II)

(III)

(IV)

(V)

(VI)

50 55 Throughout the specification, the symbol R₇ represents lower alkyl, cycloalkyl, aryl, and aralkyl.

DETAILED DESCRIPTION OF THE INVENTION

The compounds of Formula I are physiologically active substances which possess glucocorticoid and anti-inflammatory activity and hence can be used in lieu of known glucocorticoids in the treatment of rheumatoid arthritis, for which purpose they can be administered in the same manner as hydrocortisone, for example, the dosage being adjusted for the relative potency of the particular steroid. In addition, the compounds of this invention can be used topically in lieu of known glucocorticoids in the treatment of skin conditions such as dermatitis, sunburn, neurodermatitis, eczema, and anogenital pruritus.

60 65 70 When given orally, the compounds of this invention may be used in a dosage range of 0.1 to 200 milligrams, preferably 0.3 to 100 milligrams. If administered topically,

the compounds of this invention may be used in the range of .01 to 5.0% by weight, preferably .05 to 2.0% by weight, in a conventional cream or lotion.

The expression "lower alkyl" refers to those alkyl groups having from 1 to 6 carbon atoms, and includes both straight and branched chains, e.g., methyl, ethyl, propyl, isopropyl, t-butyl, etc.

The expression "cycloalkyl" refers to monovalent saturated hydrocarbon rings containing from 3 to 7 carbon atoms, e.g., cyclopropyl, cyclobutyl, etc.

The expression "aryl" refers to monocyclic carbocyclic aromatic groups that may either be unsubstituted or substituted with halogen, lower alkoxy (i.e. R—O—) wherein R is lower alkyl as defined above) or lower alkyl groups (as defined above) e.g. phenyl, ethoxyphenyl, propylphenyl, chlorophenyl, tolyl, etc.

The expression "aralkyl" refers to lower alkyl groups (as defined above) substituted with an aryl group (as defined above) e.g. benzyl, phenethyl, etc.

The term "halogen" refers to F, Cl, Br and I (Cl and Br are preferred).

The novel 21-sulfinyl steroids of Formula I are steroids of the Δ^4 -pregnene series (including the pregnadiene, pregnatriene, and pregnatetraene series).

The starting materials for making the compounds of this invention are:

Steroids of this type are known (see, for example, U.S. Pat. No. 3,048,581 to Fried et al. and British Pat. No. 869,511).

The steroids of Formula I can be prepared by several different methods. One method of synthesis involves the selective oxidation of a 21-substituted thio steroid with an appropriate selective oxidizing agent:

The oxidizing agent may be any compound capable of preferentially oxidizing a divalent sulfur atom of the type present in Formula II to the corresponding sulfoxide oxidation state in the presence of hydroxy groups, keto groups and/or carbon-carbon double bonds. Iodosobenzene diacetate, N-bromo- and N-chloro-succinimide, iodo-benzene dichloride and sodium metaperiodate are exemplary of suitable oxidizing agents. Sodium metaperiodate is preferred.

The oxidation reaction is carried out in a solvent which is essentially or completely inert to the reactants and

provides some degree of solution for both the starting steroid and oxidizing agent. When sodium metaperiodate is used as the oxidizing agent, low molecular weight alcohols (e.g. methanol) are preferable solvents. Reaction of the 21-substituted thio steroid with the oxidizing agent may be carried out at temperatures ranging from about -50°C . to about $+80^{\circ}\text{C}$. preferably within a temperature range of -15°C . to $+40^{\circ}\text{C}$. for a period of time ranging from about 12 hours to 7 days, preferably from 1 to 4 days. Isolation of the 21-sulfinyl steroid may be accomplished by pouring the reaction mixture into water (if a water miscible solvent is used), filtering off the desired product and drying.

Preparation of the novel 21-substituted thio steroids of Formula II may be accomplished by reacting alkali metal salts of mercaptans (MSR_1 wherein M is an alkali metal, preferably sodium or potassium) with steroids of Formula V:

An alternative method for preparing the 21-substituted thio steroids of Formula II is to react an alkali metal salt of a mercaptan (MSR_1) with steroids of Formula VI:

Instead of iodine in the C-21 position, other halogens may be used; however, iodine is preferred.

The conversion of the steroids of either Formula V or Formula VI to the 21-substituted thio steroids of Formula II is carried out in a suitable nonreactive, polar solvent such as methanol, acetonitrile or dimethylformamide. The reaction takes from 12 hours to 7 days, preferably from 1 to 3 days at from 0°C . to 100°C ., preferably from 30°C . to 60°C . The starting steroid is reacted with from 1 to 6, preferably 1 to 3 molar equivalents of the alkali metal salt derivative of the appropriate mercaptan (i.e., HSR_1). Upon completion, the reaction is neutralized (if necessary), poured into water, and the 21-substituted thio steroid of Formula II is filtered off and dried.

Another alternative for preparing C-21 alkylthio steroids of Formula II involves the selective alkylation of the corresponding C-21 mercapto steroid of Formula III.

The alkylating agent may be represented by the formula R_1X_4 wherein X_4 may be

or a halogen. The C-21 mercapto steroid of Formula III is reacted with a slight excess of a base such as sodium hydride in a non-reactive polar solvent such as 1,2-dimethoxyethane for about 15 minutes to 24 hours, preferably for 1 to 3 hours at from $0^\circ C.$ to $+80^\circ C.$, preferably from $+30^\circ C.$ to $+50^\circ C.$ The reaction is then treated with a slight excess of the appropriate alkylating agent (R_1X_4) for about 30 minutes to 48 hours, preferably 3 to 24 hours at from $+50^\circ C.$ to $+100^\circ C.$, preferably from $+25^\circ C.$ to $+80^\circ C.$ Evaporation of the solvent gives the 21-substituted thio steroid of Formula II.

The C-21 sulfonates of Formula V can be prepared by reacting the corresponding C-21 hydroxy steroid of Formula VII with about 1 molar equivalent of a sulfonyl halide, i.e.

where Y is chlorine or bromine.

The reaction is carried out in an inert anhydrous solvent containing an appropriate hydrogen acceptor (e.g. a tertiary amine such as triethylamine or a basic heterocyclic amine such as pyridine).

15 An explained above, reaction of the C-21 hydroxy steroid of Formula VII with the sulfonyl halide may be run in an inert anhydrous solvent. Alternatively, the reaction can be run in a liquid tertiary amine or basic heterocyclic amine hydrogen acceptor. The reaction time can be from a few hours to several days, preferably from 12 to 24 hours, while the reaction temperature can be from $-80^\circ C.$ to $+40^\circ C.$, preferably between $-50^\circ C.$ and $10^\circ C.$ Upon completion the reaction is poured into cold water and the steroid of Formula V is filtered off and dried.

20 The C-21 iodo steroids of Formula VI can be obtained using well known procedures (see J. Am. Chem. Soc., 80, 250 (1958) and 81, 439 (1959); J. Org. Chem., 25, 1966 (1960)).

25 One general procedure for the preparation of a C-21 iodo steroid of Formula VI involves starting with an appropriate steroid of the following formula (i.e. a steroid unsubstituted in the C-21 position);

35 The steroid of Formula VIII is reacted with a mixture of calcium oxide, iodine, and a free radical initiator, preferably α,α' -azabisobutyronitrile, in a suitable solvent system such as tetrahydrofuran-methanol.

After a period of time of from about 30 minutes to 24 hours, preferably from 1 to 4 hours at from -30°C . to $+50^{\circ}\text{C}$, preferably $+10^{\circ}\text{C}$. to $+30^{\circ}\text{C}$. the reaction is diluted with a suitable organic solvent, such as methylene chloride, washed with an aqueous solution of a compound capable of removing excess iodine, such as sodium thiosulfate, and the organic solvent evaporated to give the C-21 iodo steroid of Formula VI.

Another procedure for the preparation of C-21 iodo steroid of Formula VI involves reacting a C-21 sulfonate steroid of Formula V with an alkali metal iodide salt, preferably sodium or potassium, in a polar, non-reactive solvent such as acetone or a lower molecular weight alcohol.

The reaction time may be from about 30 minutes to 48 hours, preferably from 1 to 24 hours at from -20°C . to $+100^{\circ}\text{C}$. preferably from $+10^{\circ}\text{C}$. to $+80^{\circ}\text{C}$. The solvent is then evaporated, the residue stirred with water and the C-21 iodo steroid is filtered off and dried.

Several methods are available for the preparation of 21-mercaptop steroids of Formula III. One method involves the reaction of a C-21 acylthio steroid of Formula IV with about 1 to 5, preferably 1.1 to 3, molecular equivalents of an alkali metal (preferably sodium or potassium) salt of a lower molecular weight alcohol (e.g. sodium methoxide) or an alkali metal carbonate (e.g. potassium carbonate) in a wet, non-reactive polar solvent such as the corresponding alcohol (e.g. methanol) or dimethyl sulfoxide.

The reaction time is from about 1 hour to 5 days, preferably 6 hours to 2 days at from -10°C . to $+80^{\circ}\text{C}$, preferably from $+20^{\circ}\text{C}$. to $+50^{\circ}\text{C}$. Upon completion, the reaction is treated with a low molecular weight carboxylic acid (e.g. acetic acid) equivalent to the amount of base used, and poured into water. The product is filtered off and dried.

An alternative method for the preparation of the 21-mercaptop steroids of Formula III involves the reaction of a C-21 substituted steroid of Formula V or Formula VI (or Formula VI with a halogen other than iodine in the C-21 position) with an alkali metal (preferably sodium or potassium) salt of hydrogen sulfide (i.e. MSH) in a polar solvent such as dimethyl formamide or a lower molecular weight alcohol such as ethanol.

In the second equation, other halogens may be substituted for iodine in the steroid of Formula VI. The reaction time is from about 15 minutes to 4 days, preferably 30 minutes to 2 days, at from $+25^{\circ}\text{C}$. to $+200^{\circ}\text{C}$, preferably from $+60^{\circ}\text{C}$. to $+150^{\circ}\text{C}$. Upon completion, the reaction is concentrated to a small volume, cooled, neutralized with one equivalent of a strong acid (e.g. hydrochloric acid), poured into five volumes of water, and the C-21 mercaptop steroid of Formula III is filtered off and dried.

The 21-acylthio steroids of Formula IV can be prepared by reacting a steroid of Formula V or Formula VI (or Formula VI with a halogen other than iodine in the C-21 position) with about 1 to 5, preferably 1 to 3, molecular equivalents of an alkali metal (preferably potassium) salt of a thio carboxylic acid of formula

in a non-reactive polar solvent such as acetone or dimethylformamide.

The diagram below is a summary of the above described processes for producing the novel compounds of this invention. In the diagram, the symbol "K" represents:

60 In the following examples all reactions are run under an inert atmosphere (e.g. argon), at room temperature, using anhydrous solvents unless otherwise indicated; in addition, reactions which are heated are subsequently cooled to room temperature for work-up. Steroids named as 9-halo refer to the 9 α -halo.

9-fluoro - 11 β ,16 α ,17,21 - tetrahydroxypregna-1,4-diene-3,20-dione, 21-p-toluenesulfonate, cyclic 16,17-acetal with acetone

70 To 2.9 g. of 9-fluoro-11 β ,16 α ,17,21-tetrahydroxypregna-1,4-diene-3,20-dione, cyclic 16,17-acetal with acetone dissolved in 30 ml. of dry pyridine at -56° C. is added a 0° C. solution of 1.8 g. of p-toluenesulfonyl chloride in 75 18 ml. dry methylene chloride. The reaction is stirred at

In the second equation, other halogens may be substituted for iodine in the steroid of Formula VI. The reaction time is from about 1 hour to 4 days, preferably from 3 hours to 2 days, at from 0° C. to +100° C., preferably from +30° C. to +70° C. The solvent is evaporated, the residue stirred with water, and the product filtered off and dried.

—30° C. for 2 hours and then at —5° C. for 96 hours. The reaction is poured into chloroform and washed consecutively with water, dilute hydrochloric acid, dilute aqueous sodium carbonate and water. The chloroform solution is dried with sodium sulfate and the solvent evaporated to give the crude title compound. After stirring with water, the product is filtered off, dried and recrystallized from a mixture of acetone-hexane, M.P. is 248–249° C.

EXAMPLE 49

9-fluoro-11 β ,16 α ,17-trihydroxy-21-(methylsulfinyl)-pregna-1,4-diene-3,20-dione, cyclic 16,17-acetal with acetone

- 5 Method A: 2.0 g. of 9-fluoro-11 β ,16 α ,17-trihydroxy-21-(methylthio)pregna-1,4-diene-3,20-dione, cyclic 16,17-acetal with acetone and 0.92 g. of sodium metaperiodate in 400 ml. of methanol is stirred at 5° C. for five days. An additional 0.92 g. of sodium metaperiodate is added at the end of the first and fourth day. The solvent is then evaporated. The crude product is dissolved in 400 ml. chloroform, washed with water, dried and chromatographed on a 20 g. Florisil column. 300 ml. of chloroform eluant is discarded. The column is then eluted with 500 ml. ethyl acetate followed by 400 ml. acetone. These fractions are combined and the solvents evaporated to give the product. After recrystallization from methylene chloride-petroleum ether, the product has a M.P.=234-236° C.
- 10 Method B: To 4.64 g. of 9-fluoro-11 β ,16 α ,17-trihydroxy-21-(methylthio)-pregna-1,4-diene-3,20-dione, cyclic 16,17-acetal with acetone in 800 ml. of methanol at 5° (ice water-salt bath cooling) is added, portionwise, 1.33 g. of N-chlorosuccinimide at such a rate that the internal temperature of the reaction does not exceed 10° C. After stirring at 5° for two days, the solvent is evaporated. The residue is dissolved in chloroform and washed successively with cooled, dilute aqueous sodium hydroxide and then water.
- 15 The organic phase is then dried, filtered and the solvent evaporated to give the title compound.
- Method C: 4.64 g. of 9-fluoro-11 β ,16 α ,17-trihydroxy-21-(methylthio)-pregna-1,4-diene-3,20-dione, cyclic 16,17-acetal with acetone and 3.22 g. of iodosobenzene diacetate in 100 ml. glacial acetic acid are refluxed for 4 hours. After standing for 16 hours at room temperature, the reaction is filtered, heated to near its boiling point and diluted with 450 ml. hot water. After standing at room temperature overnight, the reaction is concentrated to ca. 200 ml., cooled to room temperature and the title compound filtered off.
- 20 Method D: To 4.64 g. of 9-fluoro-11 β ,16 α ,17-trihydroxy-21-(methylthio)-pregna-1,4-diene-3,20-dione, cyclic 16,17-acetal with acetone in 200 ml. of 10% (V/V) aqueous pyridine at 20° C., is added, dropwise, with stirring, 2.75 g. of iodosobenzene dichloride in anhydrous pyridine. Direct sunlight is avoided. After ten hours, the reaction is diluted with chloroform and washed successively with dilute aqueous sulfuric acid and then water. After drying, the organic phase is evaporated to give the title compound.

EXAMPLE 97

Following the procedure of Example 74 but substituting 9-fluoro-11 β ,16 α ,17-trihydroxy-21-iodopregna-1,4-diene-3,20-dione, cyclic 16,17-acetal with acetone for 9-fluoro-11 β ,16 α ,17,21-tetrahydroxypregna-1,4-diene-3,20-dione, 21-p-toluenesulfonate, cyclic 16,17-acetal acetone in Example 74, gives 9-fluoro-11 β ,16 α ,17-trihydroxy-21-mercaptopregna-1,4-diene-3,20-dione, 21-acetate, cyclic 16,17-acetal with acetone.

EXAMPLE 98

9-fluoro-11 β ,16 α ,17-trihydroxy-21-mercaptopregna-1,4-diene-3,20-dione, cyclic 16,17-acetal with acetone

Method A: 4.0 g. of 9-fluoro-11 β ,16 α ,17-trihydroxy-21-mercaptopregna-1,4-diene-3,20-dione, 21-acetate, cyclic 16,17-acetal with acetone and 0.62 g. of sodium methoxide in 115 ml. dry methanol are stirred for four days at room temperature. After acidifying with 3.3 ml. glacial acetic acid, the product is filtered off, washed with cold water and dried. Several recrystallizations from a mixture of dimethyl formamide and methanol give a product with a M.P. of 315-316° C.

Method B through F: Following the procedure of Method A, but substituting the bases in Column I below and the solvents in Column II below for sodium methoxide and for methanol, respectively, in Method A the title compound is obtained.

Method	Column I	Column II
B	Sodium ethoxide	Ethanol.
C	Potassium ethoxide	Do.
D	Potassium i-propoxide	Isopropanol.
E	Potassium bicarbonate	5% aqueous methanol.

EXAMPLE 121

9-fluoro-11 β ,16 α ,17-trihydroxy-21-(methylthio)-pregna-1,4-diene-3,20-dione, cyclic 16,17-acetal with acetone

4.5 g. of 9-fluoro-11 β ,16 α ,17-trihydroxy-21-mercaptopregna-1,4-diene-3,20-dione, cyclic 16,17-acetal with acetone and 0.25 g. of sodium hydride in 300 ml. of 1,2-dimethoxyethane is stirred for two hours at 50°. To the reaction is then added, in a dropwise manner, 1.56 g. of methyl iodide in 25 ml. 1,2-dimethoxyethane. Stirring is continued at 50° C. for 2 days. The solvent is evaporated to give the crude product which is recrystallized from an acetone-petroleum ether mixture.

EXAMPLES 122-138

Following the procedure of Example 121 but substituting the 21-mercaptop steroids in Column I below for 9 α -fluoro-11 β ,16 α ,17-trihydroxy-21-mercaptopregna-1,4-diene-3,20-dione, cyclic 16,17-acetal with acetone in Example 121, the corresponding 21-methylthio steroids indicated in Column II are obtained.

EXAMPLE 139

9-fluoro-11 β ,16 α ,17-trihydroxy-21-iodopregna-4-ene-3,20-dione, cyclic 16,17-acetal with acetone

To a rapidly stirred mixture of 7.45 g. of 9-fluoro-11 β ,16 α ,17-trihydroxy-21-iodopregna-4-ene-3,20-dione, cyclic 16,17-acetal with acetone, 9.90 g. of calcium oxide and 0.33 g. α , α '-azabis(isobutyronitrile) in 200 ml. tetrahydrofuran-

methanol (1:1), is added dropwise a solution of 6.6 g. iodine in 33 ml. tetrahydrofuran and 19 ml. methanol. The reaction is stirred for three hours, poured into methylene chloride and filtered. The filtrate is washed with 3% aqueous sodium thiosulfate, water and solvent evaporated at below 40° C. to give the title compound.

EXAMPLE 140

9-fluoro-11 β ,16 α ,17-trihydroxy-21-iodopregna-1,4-diene-3,20-dione, cyclic 16,17-acetal with acetone

To 3.21 g. of 9-fluoro-11 β ,16 α ,17,21-tetrahydroxy-21-mercaptopregna-1,4-diene-3,20-dione, 2-p-toluenesulfonate, cyclic 16,17-acetal with acetone in 35 ml. acetone is added 2.88 g. of sodium iodide in 25 ml. acetone. The reaction is refluxed for eight hours, evaporated to a volume of ca. 8 ml. and cooled. 10 ml. of 0.1 N sodium thiosulfate is added and the reaction is cooled to 0° C. The title compound is filtered off and dried.

EXAMPLE 158

9-fluoro-11 β ,16 α ,17-trihydroxy-2-mercaptopregna-1,4-diene-3,20-dione, cyclic 16,17-acetal with acetone

Method A: A solution containing 5.9 g. of sodium ethoxide in 100 ml. of dimethylformamide is saturated with dry hydrogen sulfide. To this solution is added 14.7 g. of 9-fluoro-11 β ,16 α ,17,21-tetrahydroxypregna-1,4-diene-3,20-dione, 21-p-toluenesulfonate, cyclic 11,17-acetal with acetone in 50 ml. of dimethylformamide. After heating for 12 hours at 100°, the reaction is concentrated to a volume of ca. 30 ml., cooled, treated with 7.25 ml. concentrated hydrochloric acid and poured into 90 ml. of water. The title compound is filtered off and dried.

Method B: Following the procedure of Method A, but substituting 9-fluoro-11 β ,16 α ,17-trihydroxy-21-iodopregna-1,4-diene-3,20-dione, cyclic 16,17-acetal with acetone for 9-fluoro-11 β ,16 α ,17,21-tertahydroxypregna-1,4-diene-3,20-dione, 21-p-toluenesulfonate, cyclic 16,17-acetal with acetone in Method A, gives the title compound.

What is claimed is:

1. A compound having the structure

wherein R₁ is lower alkyl of 1 to 6 carbon atoms, cycloalkyl of 3 to 7 carbon atoms, monocarbocyclic aryl, or monocarbocyclic aralkyl; R₂ is hydrogen, lower alkyl of 1 to 6 carbon atoms, or hydroxy; R₃ is hydrogen, lower alkyl of 1 to 6 carbon atoms, methylene, or hydroxy; or R₂ and R₃ may together form a cyclized dioxolo group of the structure

or a cyclized oxazole group of the structure

wherein R₄ and R₅ are the same or different and are hydrogen, lower alkyl of 1 to 6 carbon atoms or monocarbocyclic aryl or R₄ and R₅ together form a cycloalkyl group of 3 to 7 carbon atoms and wherein R₆ is lower alkyl of 1 to 6 carbon atoms; X₁ is hydroxy or halogen; X₂ is hydrogen or halogen; and X₃ is hydrogen, lower alkyl of 1 to 6 carbon atoms or halogen.

2. A compound according to claim 1 wherein R₂ and R₃ together form a cyclized dioxolo group having the structure

22

3. A method of preparing a compound having the structure:

wherein R₁ is lower alkyl of 1 to 6 carbon atoms, cycloalkyl of 3 to 7 carbon atoms, monocarbocyclic aryl, or monocarbocyclic aralkyl; R₂ is hydrogen, lower alkyl of 1 to 6 carbon atoms, or hydroxy; R₃ is hydrogen, lower alkyl of 1 to 6 carbon atoms, methylene, or hydroxy; or R₂ and R₃ may together form a cyclized dioxolo group of the structure

or a cyclized oxazole group of the structure

wherein R₄ and R₅ are the same or different and are hydrogen, lower alkyl of 1 to 6 carbon atoms or monocarbocyclic aryl or R₄ and R₅ together form a cycloalkyl group of 3 to 7 carbon atoms and wherein R₆ is lower alkyl of 1 to 6 carbon atoms; X₁ is hydroxy or halogen; X₂ is hydrogen or halogen; and X₃ is hydrogen, lower alkyl of 1 to 6 carbon atoms or halogen, which comprises reacting a compound having the structure:

with an oxidizing agent selected from the group consisting of iodosobenzene diacetate, N-bromosuccinimide, N-chloro-succinimide, iodobenzene dichloride, and sodium metaperiodate.

4. A compound according to claim 1 wherein X₂ is halogen.

5. A compound according to claim 4 wherein the halogen is fluoro.

6. A compound according to claim 1 wherein the pregnene is a pregn-4-ene.

7. A compound according to claim 1 wherein the pregnene is prena-1,4-diene.

UNITED STATES PATENT OFFICE
CERTIFICATE OF CORRECTIONPatent No. 3,803,133 Dated April 9, 1974Inventor(s) B. Richard Vogt

It is certified that error appears in the above-identified patent and that said Letters Patent are hereby corrected as shown below:

Column 2, line 28, the word "leu" should be: -- lieu --.

Column 4, formula II, lines 21 through 34 and formula II, lines 45 through 58, that portion of the formula reading:

Column 6, line 23, delete the word "could" and insert the word:
-- cold --.

Column 6, line 45, formula VIII, that portion reading:

Column 14, line 55, the word "procedurde" should be:
-- procedure --.

Column 16, line 40, Example 81, Column I, insert a hyphen (-) after the word "methylpregna".

Column 15, line 54, Example 69, Column II, the word "dlene"
should be: -- diene --.

CERTIFICATE OF CORRECTIONPatent No. 3,803,133 Dated April 9, 1974Inventor(s) E. Richard Vogt

It is certified that error appears in the above-identified patent and that said Letters Patent are hereby corrected as shown below:

Column 16, line 53, Example 85, Column I, that portion reading: "cyclic 16,27-" should be: -- cyclic 16,17- --.

Column 16, line 63, Example 89, Column II, that portion reading: "ercapto" should be: -- mercapto --.

Column 16, line 65, Example 90, Column I, that portion reading: "1,4-dione-" should be: -- 1,4-diene- --.

Column 18, line 19, Example 107, Column I, after the words: "3,20-dione" insert: -- 21-acetate, cyclic --.

Column 18, line 18, Example 107, Column II, the word reading: "pergna-" should be: -- pregnan- --.

Column 19, line 6, "0.25 g" should be: -- 0.24 g --.

Column 19, line 59, Example 135, Column I, the word "diore" should be: -- dione --.

Column 20, line 53, Example 148, Column II, the word "methyl-prengna-" should be: -- methylpregna- --.

Column 20, line 60, Example 150, Column I, that portion reading: "14,diene-" should be: -- 1,4-diene- --.

Column 20, line 70, Example 154, Column II, delete the colon (:) and insert in its place a hyphen (-).

Column 21, line 18, "tetrahydروxypyregna-" should be: -- tetrahydroxypregna --.

Column 21, line 19, "11,17-acetal" should be: -- 16,17-acetal --.
